SUPPORTING BASE AND COVER FOR WINDOW LOCKS

Arthur J. Rochow, Pittsford, N. Y.

Application February 27, 1948, Serial No. 144,776

Term of patent 3½ years

(Cl. D10—10)

To all whom it may concern:

Be it known that I, Arthur J. Rochow, a citizen of the United States, residing at Pittsford, in the county of Monroe and State of New York, have invented a new, original, and ornamental Design for Supporting Base and Cover for Window Locks, of which the following is a specification, reference being had to the accompanying drawing, forming part thereof.

Fig. 1 is a top plan view of a supporting base and cover for window locks, showing my new design;

Fig. 2 is a side elevation;

Fig. 3 is a front elevation, and

Fig. 4 is a central, vertical section thereof.

I claim:

The ornamental design for a supporting base and cover for window locks, substantially as shown.

ARTHUR J. ROCHOW.
